UNITED STATES PATENT OFFICE.

JAMES GREER, OF HOBOKEN, NEW JERSEY.

DEVICE FOR HEATING SWITCHES AND THE LIKE.

1,388,997.

Specification of Letters Patent. Patented Aug. 30, 1921.

Application filed May 3, 1921. Serial No. 466,541.

To all whom it may concern:

Be it known that I, JAMES GREER, a citizen of the United States, residing at Hoboken, in the county of Hudson and State of New Jersey, have invented a new and useful Improvements in Devices for Heating Switches and the like, of which the following is a specification.

This invention relates to devices for heating railroad switches and the like to prevent snow and ice from interfering with the operation thereof.

The objects of the invention are to provide a device of this kind which can be readily operated so that the melting of snow and ice is greatly facilitated and a large amount of labor is saved; also to provide a device of this kind which projects the liquid directly upon the parts to be heated, and consequently requires a comparatively small amount of inflammable liquid to produce the desired result; also to provide a device of this kind with a pilot light which ignites the liquid discharged from the device; also to provide a device of this kind which is particularly adapted for use with low flash liquids; also to improve the construction of devices of this kind in other respects hereinafter specified.

30 In the accompanying drawings:

Figure 1 is a side elevation of the heating device embodying the invention.

Fig. 2 is a fragmentary side elevation thereof, partly in section, on an enlarged scale, showing the pilot burner.

Fig. 3 is a fragmentary side elevation thereof showing one of the discharge nozzles.

Fig. 4 is a fragmentary sectional elevation thereof on line 4-4, Fig. 2.

Fig. 5 is a top plan view of a switch showing the device installed thereon.

Liquids having low flash points have heretofore been used for melting snow and ice on switches, manhole covers and the like, but these liquids have heretofore been applied to the part to be heated by means of a can or container having a burner which ignites the liquid as it is poured from the can.

50 The invention herein described is particularly desirable when used in connection with railroad yards having a large number of switches, and when so used, makes it possible for one man to accomplish work heretofore done by a considerable number of men.

Briefly stated, the switch heating device

includes a pipe line connected with a suitable supply of inflammable liquid and having a plurality of liquid-projecting, spraying or distributing devices, one of these devices being installed on each switch. The switch heating devices are preferably, though not necessarily provided with pilot burners which are arranged in operative relation to the discharge nozzles for the inflammable liquid so that the pilot burners ignite the liquid as it is discharged from the nozzles. Consequently, in order to heat a switch, it is only necessary to open for an interval of time, a valve connecting the liquid spraying device for the particular switch with the pipe line to discharge liquid on the switch to melt the ice or snow thereon, the opening of the valve preferably also serving to replenish the supply of fuel in the pilot burners.

In the particular embodiment of the invention shown in the drawings, A represents a storage tank or reservoir for the liquid, which may be arranged in any desired position relatively to the switches. In case the tank is arranged sufficiently high above the track level, the liquid may be discharged to the various liquid projecting devices by gravity. On the other hand, if the tank is not located at a sufficient height, the liquid therein may be discharged from the tank by means of air pressure admitted to the tank by a pipe B receiving air from any suitable source of pressure, for example, from a high pressure pipe line b which is connected with the pipe B through the medium of a pressure reducing valve or the like b'. The inflammable liquid flows from the tank to a supply line C, the flow to the supply line being controlled by suitable valves c. This supply line may lead to the various switches in the yards and connects by means of branch pipes D with the various liquid-projecting devices. The flow of liquid to each branch pipe is controlled by means of a valve d or the like. Any other means for supplying liquid to the projecting devices of the several switches may be employed.

Each liquid-projecting device comprises one or more distributing pipes E arranged in proximity to the parts of the switch and each of these pipes is provided at intervals with discharge nozzles F for the inflammable liquid. Two distributing pipes are employed in the construction shown, and are arranged at opposite sides of the switch and connected

by means of a connecting pipe *e* which is preferably arranged underneath the tracks and out of contact therewith so that if the rails form electrical conductors for a signal system, the connecting pipe *e* will not interfere with the operation of the signal system. The pipes *E* are connected with the pipe line *C* by means of the branch pipes *D*, so that when the valve *d* is opened, the inflammable liquid will pass to the connecting or distributing pipes.

The discharge or projecting nozzles *F* may be of any suitable construction, those shown in the drawings each consisting of a small pipe or nipple *f* which is provided with an orifice through which the liquid is discharged. The nipple is connected by any suitable pipe connections such, for example, as two standard L's *f*' *f*'' to a T or coupling *f*''' forming a part of the pipe *E*. The discharge nozzles may be arranged in any desired position to project the liquid where it is most needed, most of the nozzles shown being arranged to direct the jet of liquid crosswise of the rails toward the middle of the track, and the nozzles are preferably arranged substantially midway between the ties *X* so that the jets of liquid will be directed into the spaces between the ties rather than upon the ties themselves. Discharge nozzles of any other suitable construction may be provided.

The distributing pipes *E* of the liquid-projecting devices may be supported from the track in any desired manner, supporting brackets *G* being preferably employed, which may be spiked or otherwise secured to the ties *X*. These brackets are provided at their upper portions with apertures or eyes *g* through which a distributing pipe may pass, and the pipe is preferably supported in the desired position relatively to the brackets by means of set screws *g*' and *g*'', Figs. 2 and 4. In this manner the distributing pipes can be readily adjusted to the desired elevations. These pipes and the discharge nozzles *F* are preferably arranged to discharge the jets of liquid to the tops of the rails, so that liquid will flow down or along the surfaces of the rails and will heat all portions thereof.

The liquid discharged from the nozzles *F* may be ignited in any desired manner, the liquid used being highly inflammable so that the ignition of the liquid discharged from one of the nozzles will readily cause the ignition of liquid discharged from all of the nozzles. While the device may be used without any special means for igniting the liquid, yet it has been found desirable to provide pilot burners in operative relation to some of the nozzles so that it is possible to operate the switch heating device by merely opening the valve *d* for a short interval of time. In the construction shown for this purpose, a plurality of pilot burners *H* is provided which are arranged at opposite ends of the pipes *E*.

Each of the pilot burners includes a base or reservoir *h* provided with threaded bosses or projections *h*' and *h*'' to which the various pipes of the heating device may be connected. By means of this construction the reservoir *h* forms a connecting means for the various pipes of the device as well as forming a base and reservoir for the pilot burner. The burner proper is arranged at the top of the reservoir *h* and in the construction shown includes a screw cap *h*''' having a threaded engagement with the upper end of the reservoir *h* and having a short pipe or tube *h*'' extending upwardly therefrom. Within the pipe *h*'' is arranged a wick *h*'' which may be made of any suitable material and which extends below the tube *h*'' into the reservoir *h*. If desired, the lower end of the wick may be arranged in a screen or container *h*'' which holds the wick substantially centrally in the reservoir *h* and prevents the wick from interfering with the flow of liquid through the reservoir *h*.

In order to make certain that the pilot burner will ignite the liquid discharged by the various nozzles, the following construction is preferably employed. A pipe or tube *I* is connected to one of the threaded bosses of each reservoir *h* and is provided at its upper end with a discharge nozzle *i* adapted to direct a jet of inflammable liquid through the flame of the wick *h*'' and toward the other discharge nozzles of the heating device. The jet will be discharged from the ignition nozzle *i* only when the fluid is supplied to the device under pressure and will throw a stream of burning liquid near enough to the jets discharged from the nozzles *F* to ignite the liquid discharged therefrom. In the construction shown, two pilot burners are arranged at opposite ends of the connecting pipe *e* at the outside of the rails and two other pilot burners are arranged at the opposite ends of the pipes *E* and are arranged at the inner sides of the rails, the discharge nozzles from the latter pilot burners projecting a jet of burning liquid at those parts of the switch which are most likely to be rendered inoperative by the accumulation of ice or snow. By means of this arrangement the pilot burners are located at four different points so that ignition of the liquid discharged from all of the nozzles is insured, regardless of the direction and force of the wind. Any other arrangement of the pilot burners with reference to the liquid-projecting device may, however, be provided.

The various pipes of the switch-heating device may be connected to any desired threaded lugs of the reservoir *h* and those lugs which are not necessary for pipe connections may be closed by the usual plugs or other means (not shown).

In the operation of the device, if the same has been out of use for an interval

of time, it is necessary to pour some inflammable liquid on one or more of the wicks of the pilot burners and then to ignite the same or to use other means for igniting the liquid discharged from the nozzles F. The valve d is then opened to supply the liquid-projecting device with the inflammable liquid. Under ordinary conditions it is only necessary to have the valve d open for a few seconds. After the first operation of the device the pilot burners will become filled with inflammable liquid and will burn for a considerable interval of time on the liquid in the reservoir as well as that remaining in the distributing pipes. When the device is actuated for the second time, it is only necessary to open the valve d for a short space of time to project sufficient liquid on the tracks, switch points and rails to melt all snow and ice thereon. Consequently, in clearing switches of snow and ice, so little time is taken up by the opening and closing of the valves d that one man can take care of a very much larger number of switches than was heretofore possible. The device described has the advantage that the inflammable liquid is projected directly to the parts to be cleared of ice and snow so that the heat of the flame is effectively used to cause melting of the ice and snow and the evaporation of the water resulting from such melting, the liquid used having its flash point low enough to burn while on the ice or snow. Furthermore, any water formed by the melting of the ice and snow and not evaporated is free to drain from the track, and does not in any way interfere with the operation of the device. The heating device shown in the drawings is simple and inexpensive to construct, being made mostly of standard pipe fittings, and can be readily installed on a switch and removed therefrom, so that the devices can be installed in the fall of the year and again removed from the switches in spring. The device is also safe to operate since the ignition of the liquid may be controlled at a distance from the switch which is being heated by locating the valve d at a suitable distance therefrom.

While the device embodying this invention has been described as adapted particularly for melting ice and snow on railroad switches, yet it will be understood that it is not intended to limit the device to use on railroad switches since the same may be used for melting ice and snow from other mechanisms or parts.

I claim as my invention:

1. In a device for heating switches, the combination of a pipe arranged in proximity to a rail forming a part of the switch, and a plurality of nozzles in said pipe adapted to project an inflammable liquid upon said rail, said liquid being ignited

after the same is discharged from said nozzles.

2. In a device for heating switches, the combination of a supply of low flash point liquid, a pipe arranged lengthwise of the switch and connected with said supply of liquid, and discharge nozzles on said pipe which direct streams of said liquid at the rails forming a part of the switch.

3. The combination with a switch including rails and ties, of a heating device for said switch including a pipe, means for supplying a low flash liquid to said pipe, and discharge nozzles on said pipe which are adapted to direct jets of said liquid on the rails and into the spaces between said ties.

4. The combination with a switch including rails and ties, of a heating device for said switch including pipes arranged beyond the outer sides of said rails, means for supplying inflammable liquid to said pipes, and nozzles on said pipes for directing jets of said liquid to said rails, said liquid being ignited after the same is discharged from said nozzles.

5. In a device for heating switches, the combination of a pipe arranged in proximity to a switch, a plurality of nozzles in said pipe for projecting an inflammable liquid on said switch, and means for igniting said liquid after the same is discharged from said nozzles.

6. In a device for heating switches, the combination of a distributing device secured in proximity to a switch and adapted to direct inflammable liquid on the switch, and an ignition device having a flame through which a part of the liquid from the distributing device passes to ignite the liquid projected from said distributing device.

7. In a device for heating switches, the combination of means secured on a switch for distributing inflammable liquid on the rails of the switch, and means also secured on said switch for igniting the liquid distributed on said rails, whereby the inflammable liquid burns while on the rails.

8. In a device for heating switches, the combination of distributing pipes extending lengthwise of a switch, nozzles on said pipes and adapted to direct liquid in a direction transversely of the switch, and an ignition device including a nozzle adapted to direct a jet of burning liquid across the jets directed from said first mentioned nozzles.

9. In a device for heating switches, the combination of distributing pipes extending lengthwise of a switch, nozzles on said pipes and adapted to direct liquid in a direction transversely of the switch, and an ignition device including a pilot burner and a nozzle adapted to direct a jet of liquid through a flame from said burner and across the jets directed from said first mentioned nozzles.

10. In a device for heating switches, the

combination of a pilot burner having a base forming a reservoir for fuel and arranged in proximity to a switch, means for supplying fuel under pressure to said reservoir, and 5 a nozzle also connected with said supply means and arranged to project a jet of liquid through the flame of said pilot burner and on said switch.

11. In a device for heating switches, the 10 combination of a pilot burner having a base forming a reservoir for fuel and arranged in proximity to a switch, means for supplying fuel under pressure to said reservoir, a pipe leading upwardly from said reservoir, 15 and a nozzle on said pipe arranged to direct a jet of liquid through the flame of said pilot burner and on said switch.

12. In a device for heating switches, the 20 combination of a pilot burner having a base forming a reservoir for fuel and arranged in proximity to a switch, means for supplying fuel under pressure to said reservoir, a pipe leading upwardly from said reservoir, a 25 nozzle on said pipe arranged to direct a jet of liquid through the flame of said pilot burner and on said switch, and a plurality of nozzles receiving liquid from said supply means and arranged to project liquid on said switch, said last mentioned nozzles projecting liquid toward the jet projected from said 30 first mentioned nozzle, whereby the liquid projected from all of said nozzles is ignited.

13. In a device for heating switches, the 35 combination of distributing pipes extending lengthwise of a switch, nozzles on said pipes and adapted to direct liquid on the switch, pilot burners at opposite ends of said pipes,

and nozzles adjacent to said pilot burners and arranged to project liquid through the 40 flames of said pilot burners and toward the liquid projected from said first mentioned nozzles.

14. In a device for heating switches, the 45 combination of distributing pipes extending lengthwise of a switch, nozzles on said pipes, pilot burners having reservoirs for the liquid, said pipes being connected with said reservoirs, and liquid supply pipes which are also connected to said reservoirs. 50

15. In a heating device, the combination 55 of a main supply pipe, a supply of inflammable liquid connected with said main supply pipe, branch supply pipes, distributing pipes arranged adjacent to the parts to be heated, nozzles in said distributing pipes for directing liquid to said parts, valves in said branch pipes and arranged at a distance from said parts for controlling the flow of liquid to said nozzles, and an ignition device 60 for igniting the liquid discharged from said distributing pipes.

16. In a heating device, the combination 65 of means for distributing liquid on the parts to be heated, and a pilot burner for igniting the distributed liquid, said burner including a base portion forming a reservoir for inflammable liquid, a wick extending into said base portion, a pipe connected to said base portion and extending upwardly therefrom, 70 and a discharge nozzle on said pipe adapted to project a jet of liquid through the flame on said wick.

JAMES GREER.
